No. 714,600.

Patented Nov. 25, 1902.

E. W. MÜLLER.

OUTLET BOX.

(Application filed Mar. 12, 1902.)

(No Model.)

UNITED STATES PATENT OFFICE.

ERNEST W. MÜLLER, OF BROOKLYN, NEW YORK, ASSIGNOR TO HUBERT KRANTZ, OF BROOKLYN, NEW YORK.

OUTLET-BOX.

SPECIFICATION forming part of Letters Patent No. 714,600, dated November 25, 1902.

Application filed March 12, 1902. Serial No. 97,952. (No model.)

To all whom it may concern:-

Be it known that I, ERNEST W. MÜLLER, a citizen of the United States of America, residing in the borough of Brooklyn, in the 5 county of Kings, State of New York, have invented an Improved Outlet-Box, of which the following is a specification.

The object of my invention is to construct an outlet-box which shall be specially adapted for use in connection with electric-arc lamps or the larger types of Nernst lamps or other electrical devices which have to be suspended from above, more especially from the ceilings of buildings.

15 In the accompanying drawings, Figure 1 is a vertical section of my improved outlet-box, and Fig. 2 is an inverted plan view of the same.

In the common practice electric-arc lamps 20 when used in buildings are suspended from hooks fastened in the ceiling, and the conductor-wires are led from adjacent outlets if interior wiring has been used. I so construct my outlet-box that the lamp can be suspended 25 directly from the box itself, thus providing a self-contained structure complete in itself and dispensing with the separate fitting of the outlet-box and supporting-hook heretofore required.

30 The outlet-box A, which is to be fitted in place in the ceiling C in any suitable way, is shown in the present instance as cylindrical. It may be suspended from the floor above by a pipe B, coupled up to the bottom or back 35 of the box, into which is also fitted a pipe B' for leading in the wires E E for connection with the lamp.

The face-plate of the outlet-box I prefer to make in the form of an open-work spider D 40 for convenience in connecting up the wires.

This spider is secured to the face of the box by means of screws d, fitting holes tapped in the ribs a, formed in the walls of the box. To the center of this spider is fitted a suspension-hook F with intermediate insulating washers f f. The eye k at the upper end of the lamp to be suspended fits over this hook, and a sheet-metal cover or canopy K, adjustable on the upper part of the frame of the lamp or the like, may be used to cover up the 45 support and outlet-box, the larger upper end of this canopy or cover fitting against the ceiling C.

I claim as my invention—

1. An electrical outlet-box adapted to be 55 fitted into a ceiling and carrying on its lower face an insulated suspension-hook for an arc-lamp or the like.

2. An electrical outlet-box adapted to be fitted into a ceiling and having a face-plate 60 carrying a suspension-hook with insulation between the hook and the face-plate.

3. An electrical outlet-box having an open-work face-plate, a suspension-hook carried by the face-plate with insulation between the 65 suspension-hook and the plate.

4. The combination of an outlet-box adapted to be fitted to a ceiling and having an insulated suspension - hook with a canopy adapted to be carried by the frame of an arc-lamp or the like to cover up the suspension-hook and the outlet-box, substantially as described.

In testimony whereof I have signed my name to this specification in the presence of 75 two subscribing witnesses.

ERNEST W. MÜLLER.
